UNITED STATES PATENT OFFICE.

WILLIAM S. WEBSTER, OF NEWARK, NEW JERSEY.

HARNESS-PAD.

SPECIFICATION forming part of Letters Patent No. 374,024, dated November 29, 1887.

Application filed September 3, 1887. Serial No. 248,649. (No model.)

To all whom it may concern:

Be it known that I, WILLIAM S. WEBSTER, of Newark, in the county of Essex and State of New Jersey, have invented a new and Improved 5 Harness-Pad, of which the following is a full, clear, and exact description.

My invention consists in forming the back-pad without a jockey, the skirt on each side being made continuous from the saddle to the 10 lower end and an opening being formed therein for the back-band to pass under the skirt at a point somewhat below the terret.

The invention also consists in providing the 15 said opening for the back-band in each skirt with a facing to imitate a jockey and to prevent wear.

The invention finally consists of the construction of the pad, all as hereinafter described and claimed.

Reference is to be had to the accompanying 20 drawings, forming a part of this specification, in which similar letters of reference indicate corresponding parts in all the figures.

Figure 1 is a perspective view of my new 25 and improved harness back-pad. Fig. 2 is an enlarged sectional elevation of the same, taken on the line xx of Fig. 1; and Fig. 3 is a detailed sectional view of the skirt and back-band.

The pad is surmounted by the saddle A, 30 which rests directly upon the upper adjacent ends of the skirts B, instead of upon a separate piece called a "jockey." The skirts B are each made in one piece from the saddle A to the tips of the pad, and a little below each terret C 35 is formed in each skirt an opening, D, for the

back-bands E to pass through under the skirts, where they are held by the terrets C in the usual or in any approved manner. Surrounding each opening D and secured to the skirt is a metal clip, F, which finishes the skirts 40 about the back-band and gives the appearance of and takes the place of a jockey. The skirts B have the pads G secured directly to them, as shown in Fig. 2, and are provided with a welt, g , at each edge, and the pads are provided at each edge with a welt, h , as shown in Fig. 2. The welts g are composed of a leather tube, g' , and suitable filling, and the welts h are composed of a tube, h' , and suitable filling. The tubes g' and h' are stitched to each edge of 45 the pad cloth or leather j by a single seam, i . This done, the welt-covering h is stitched to each edge of the skirt by a seam, i' , so that by the two seams i' at each edge of the skirt the two welts and the pad cloth or leather are all 50 secured to the skirt ready to be stuffed.

Having thus fully described my invention, I claim as new and desire to secure by Letters Patent—

1. In a harness saddle, the skirt B, formed 60 with an opening, D, faced with a clip, F, substantially as and for the purposes set forth.

2. The pad-cloth j , having the inside and outside welt-casing, $g' h'$, stitched to its edges by seams i , and the outside welt-casing stitched 65 to the skirt B, substantially as described.

WILLIAM S. WEBSTER.
